UNITED STATES PATENT OFFICE.

LOUIS KYSER AND ALFRED C. REX, OF PHILADELPHIA, PENNSYLVANIA.

DESIGN FOR A TOY MONEY-BOX.

SPECIFICATION forming part of Design No. 11,943, dated August 10, 1880.

Application filed June 2, 1880. Term of patent 3½ years.

To all whom it may concern:

Be it known that we, LOUIS KYSER and ALFRED C. REX, both of the city and county of Philadelphia, and the State of Pennsylvania, have invented an Improvement in Designs for Toy Money-Boxes, of which the following is a specification.

The configuration or design is fully set forth in the following specification, shown in the accompanying drawings, and referred to in the appended claims.

In the drawings, Figure 1 is a side elevation of our improved design for toy money-boxes. Fig. 2 is a plan of same.

15 A A are the side pieces and form the body of the box. They form, when placed together, a hexagonal prism. The body is furnished with two apparent doors directly opposite each other, and the two sides of the hexagonal 20 prism on either side and between the doors are filled with diamond or claw shaped openings.

The top B rests upon the side pieces, A A, holding them together at the top. This top 25 piece has a hexagonal periphery corresponding to the body, and all around said periphery is a raised scallop ornamentation. Rising from the top plate, B, is a dome, C, furnished with perforations or apertures corresponding 30 to those in the side piece or body, and at the top is an acorn-shaped knob, c. Between the scallop edging and dome on the top plate is a slot, E, through which the money is deposited.

The bottom or base plate, D, supports the side plates or body A, and holds them together. 35 It is inclined outward from top to bottom and is ornamented with raised ball-shaped figures around its sides.

Having now described our invention, what we claim as new, and desire to secure by Letters Patent, is—

1. The design for a toy money-box, hexagonal in shape and provided with a spherical dome, substantially as described and shown.

2. The design for a toy money-box, composed 45 of a hexagonal base, D, and hexagonal body A, having one or more of its sides to represent doors, and the other sides perforated, top B, having a slot, E, and a raised perforated dome, C, substantially as described, and shown in 50 the accompanying drawings.

3. The design for a toy money-box, composed of a body with equal sides, perforated and hexagonal in shape, and surmounted by a spherical dome, substantially as described and 55 shown.

In testimony of which invention we hereunto set our hands.

LOUIS KYSER,
ALFRED C. REX.
